UNITED STATES PATENT OFFICE.

JULES HAUVENTTE-MICHELIN, OF NEW BRUNSWICK, NEW JERSEY, ASSIGNOR TO
MICHELIN TIRE COMPANY, OF MILLTOWN, NEW JERSEY, A CORPORATION OF
NEW JERSEY.

DESIGN FOR A TIRE TREAD.

Application filed October 30, 1925. Serial No. 15,293. Term of patent 14 years.

To all whom it may concern:

Be it known that I, JULES HAUVENTTE-MICHELIN, a citizen of France, residing at New Brunswick, in the county of Middlesex and State of New Jersey, have invented a new, original, and ornamental Design for Tire Treads, of which the following is a specification, reference being had to the accompanying drawings, forming a part thereof, in which—

Figure 1 is a plan view of a portion of the tread, showing the design, and

Figure 2 shows a section along the broken line 2—2 of Fig. 1, and looking in the direction of the arrows.

I claim:

The ornamental design for a tire tread, as shown.

In testimony whereof I affix my signature.
JULES HAUVENTTE-MICHELIN.
